UNITED STATES PATENT OFFICE.

THOMAS JOHNSON, OF ST. LOUIS, MISSOURI.

INSECT-EXTERMINATING APPARATUS.

SPECIFICATION forming part of Letters Patent No. 623,374, dated April 18, 1899.

Application filed November 21, 1898. Serial No. 696,997. (No model.)

To all whom it may concern:

Be it known that I, THOMAS JOHNSON, a citizen of the United States, residing at the city of St. Louis, in the State of Missouri, have invented certain new and useful Improvements in Insect-Exterminating Apparatus, of which the following is a full, clear, and exact description, reference being had to the accompanying drawings, forming part of this specification.

My invention relates to a device for killing insects by means of a blast of hot gas, the device comprising, essentially, a fount for holding hydrocarbon oil, a gas burner and generator, a blast-tube, and a pump in connection with said fount for forcing the oil to said burner.

My invention consists in the construction and details of construction hereinafter described and claimed.

Figure I is a perspective view of the apparatus. Fig. II is a vertical sectional view taken through the gas-generator. Fig. III is a horizontal sectional view taken on the line III III, Fig. II. Fig. IV is a horizontal sectional view taken on line IV IV, Fig. III. Fig. V is a vertical sectional view through the fount, showing the air-pipe from the pump.

1 designates the fount of the apparatus, 30 which is adapted to contain hydrocarbon oil, such as gasolene.

2 designates a pump-cylinder that contains a piston provided with a handle 3. The pump-cylinder is connected by an arm 4 with the upper end of the fount and by a tube 5, that provides a communication between the interior of said pump-cylinder and the interior of the fount. The pump-cylinder is adapted to serve as a handle by which the apparatus is 40 carried.

The fount 1 is provided with an inlet closed by a cap 6. Leading from the tube 5 on the interior of the fount is an upwardly-extending pipe 5, that communicates with a tube 7 at the top of the fount, (see Fig. V,) the opening in which on the interior of the fount is controlled by the inner end of a valve 8, located in the tube 7.

In the operation of the pump by manipulation of its piston air is forced through the tube 5 into the tube on the interior of the fount and up to its outlet and into the fount

when said outlet is opened by unseating the valve 8. When sufficient compression of air within the fount is obtained, the valve 8 is 55 moved inwardly to its seat, thereby shutting off the return of air through said interior pipe to the tube 5 and pump-cylinder.

9 designates a pipe having communication with the interior of the fount 1 and leading 60 upwardly therefrom. On this pipe is a cup-ring 10, provided with ports 11. Seated on the cup-ring 10 is a slotted cylinder 12, that surrounds the pipe 9, allowing a space between it and the pipe. 13 is a ring that surrounds 65 the slotted cylinder 12 and above which is mounted a cap 14, having a central opening 15, corresponding to the interior of the cylinder 12. These parts constitute the generator of the apparatus in which the hydrocarbon 70 oil is subheated to produce gas. The cap 14 is provided with a tangential inlet 16, and on the interior of the cap at said inlet is a wing 17, that deflects the jet of gas entering the generator during the operation of the apparatus, as will hereinafter appear.

18 designates a pipe leading from the pipe 9 at the upper end thereof, said pipe 18 being provided with a jet-tube 19, containing a needle-valve controlled by a valve 20. The jet 80 of the jet-tube 19 is arranged at the entrance of the inlet 16. (See Fig. I.)

21 designates a tube located at the top of the pipe 9 and having communication with said pipe. The communication between the 85 pipe 9 and tube 21 is controlled by a needle-valve 22.

23 is an air-chamber provided with a port 24, said chamber being connected to the tube 21. The chamber 23 carries a blast-tube 25, 90 having air-inlets 26, said blast-tube being open to communication with the air-chamber 23 and also open at its outer end.

27 designates a shield that protects the opening 15 at the top of the generator to protect 95 the interior of the generator from the ingress of strong air-currents—such, for instance, as would be encountered where the apparatus is used in the open air.

In the practical use of the apparatus the 100 fount 1 has hydrocarbon oil introduced into it, and the valve 8 being turned to unseat it in the tube 7 the pump is operated by manipulating the piston-handle 3 to inject air into

the fount and cause compression therein. The jet-opening in the jet-tube 19 is then opened by turning the valve 20, and after a quantity of hydrocarbon oil has been permitted to escape into the generator and fall into the cup-ring 10 the oil is ignited and the jet-opening is closed until the oil admitted to the generator has been consumed and the generator and pipe 9 have become heated. At this time the heat of the tube and generator has become sufficient to heat the ascending oil in its flow through the pipe 9 and create it into gas as it ascends. The jet-tube 19 is again opened and the gas escapes into the generator through the inlet 16 and, burning in the generator, keeps the flowing oil superheated to continue the transformation of the oil into gas. The valve in the tube 21 is then opened by operating the valve 22 to permit the flow of hot gas from the pipe 9 into the air-chamber 23, where it combines with fresh air entering said chamber through the port 24 and the air-inlets in the blast-tube 25, thereby causing a hot blast of gas to be directed through the blast-tube 25 to its outer end. The blast escaping through the open outer end of the blast-tube is of great intensity, and when the said tube is directed to discharge the blast of gas against insects they are readily killed.

This apparatus is especially valuable in exterminating insects on vines, plants, &c., but may be available in destroying them wherever found.

35 I claim as my invention—

1. In an insect-exterminator, the combination of a fount, a pump arranged in communication with said fount, a pipe communicating with said fount, a jet-tube having communication with said pipe, a blast-tube 40 having communication with said pipe; and a gas-generator comprising a cup-ring, a slotted cylinder, an outer ring surrounding said cylinder, and a cap surmounting said outer ring and cylinder, substantially as set forth. 45

2. In an insect-exterminator, the combination of a fount, a pump having communication therewith, a pipe having communication with said fount, a jet-tube carried by said pipe, a blast-tube carried by said pipe; and 50 a gas-generator surrounding said pipe and comprising a cup-ring having air-inlets, a slotted cylinder on said cup-ring, an outer ring surrounding said cylinder, a cap having a central opening and provided with an inlet, 55 substantially as described.

3. In an insect-exterminator, the combination of a fount, a pump having communication therewith, a pipe having communication with said fount, a jet-tube carried by said 60 pipe, a blast-tube carried by said pipe, a gas-generator surrounding said pipe and open at its upper end, and a shield surmounting said generator arranged to protect the open end thereof, substantially as set forth.

THOS. JOHNSON.

In presence of—
E. S. KNIGHT,
STANLEY STONER.
